(57) **CLAIM**

The ornamental design for a baby scale, as shown and described.

DESCRIPTION

FIG. 1 is a top perspective view of a baby scale showing my new design;

FIG. 2 is a front view thereof;

FIG. 3 is a top view thereof;

FIG. 4 is a left side view thereof;

FIG. 5 is a right side view thereof;

FIG. 6 is a bottom view thereof; and,

FIG. 7 is a back view thereof.

The broken lines shown are included for the purpose of illustrating portions of the baby scale that form no part of the claim.

1 Claim, 2 Drawing Sheets
